UNITED STATES PATENT OFFICE.

FRANK J. KELLY, OF BROOKLYN, NEW YORK.

CAR INDICATOR.

Application filed January 26, 1925. Serial No. 4,802.

To all whom it may concern:

Be it known that I, FRANK J. KELLY, a citizen of the United States, and a resident of Brooklyn, in the county of Kings and State of New York, have invented certain new and useful Improvements in Car Indicators, of which the following is a specification.

This invention has special reference to indicators for cars in trains where a number of them compose the train, and indicate to the passengers the next stop to be made.

One of the objects of the invention is to provide an indicator that will be placed at an intermediate portion of the car, and show on the opposite sides the next station, so that it can be read by passengers in any part of the car.

A further object of the invention is to provide a device of this character where a number of them will operate in unison and can be controlled by the operator in any one of the cars.

A further object of the invention is to provide a device of this character in which the reels carrying the web for the stations thereon can be readily removed and another web substituted for a different route of the train.

In the accompanying drawing showing one embodiment of my invention, Figure 1 is a front elevation.

Fig. 2 is a horizontal section of the line 2—2 on Fig. 1.

Fig. 3 is a diagram of the circuit for the ten car train.

Fig. 4 is a vertical section enlarged at one end of the indicator.

Fig. 5 is a cross section on the line 5—5 of the Fig. 4.

Fig. 6 is a cross section on the line 6—6 on Fig. 4.

Fig. 7 is a cross section on the line 7—7 of Fig. 4.

Fig. 8 shows the web.

Fig. 9 is a detail view of a spool hub.

The device comprises essentially an elongated frame 2 with the casings 3 and 4 at the ends. These casings are identical and the description of one will explain the other. The frame 2, shown in section in

Fig. 7 has side walls 5 and 6, each provided with an opening, 7 and 8, to expose the opposite sides of the web 9 that travels through this frame alternately in opposite directions, as desired. The frame 2 carries on each side, a frame 10 in which is mounted a glass window 11; which frames are each slidable upwardly through openings in the top wall, as clearly shown in Fig. 7. This is to permit access to the casing to insert and remove the web. It is to be understood that this web 11, will have the same stations printed on opposite portions of its two faces as indicated in Fig. 8.

Means are provided for drawing this web in opposite directions as desired through the open frame, when the stations printed in sequence throughout are exposed at the opposite windows 7 and 8. At each end of the frame I provide in the casings 3 and 4 mountings for the reel 12, on which web or band 9 is wound, and also provide means for rotating the reel, that will draw the web between guide rollers 13, 13, winding on one spool that will draw it off from the other spool. When one spool has become full, or the car is reversed in direction the spool in the other compartment is actuated, that will reverse the movement of the web.

As shown in Fig. 4 the casing 4 has frame plates 16 and 17 mounted therein, one of which carries an electric motor 18 on brackets 19. The reel 12 has its shaft 20 supported by a stop bearing 21 carried by a cross bar 22. This is removably supported by the frame ring 17 by means of headed studs 23 on the ring that pass through openings 24 in the bar 22, which openings have a narrow extension to receive the stem of the stud, that will lock the bar 22 in this position when inserted, and turned a short distance. By thus removing the stop bearing the reel can be withdrawn and another reel substituted. The lower part of the casing 4 is closed by a cap 25 held by studs 26 on the frame 17, that engage the slotted openings 27 from removably attaching these caps.

The shaft 28 of the motor carries the gear 29 that meshes with the gear 30 on bracket 19. The latter gear engages an internal

gear 31 mounted in a bearing 32 on the frame 16 and a shaft 33 of the internal gear engages the spool hub 34 by lugs 35 that enter slotted portions 36 in the hub. By this means when the reel 12 is moved upwardly it will cause engagement of the reel with the internal gear. The motor 18 will thus operate the reel 12 at a reduced speed. The frames 16 and 17 are connected by bars 37 at suitable places to form a rigid structure and support the casing 4.

Suitable means are provided to connect the end of the web to the spool. The spool 12 carrying the reel web or band is inserted, and one end is caused to pass through the frame 2, and this end of the web attached to the spool 12 in the other compartment 3 constructed identical with the compartment 4, combining the reel and motor and other parts identical with that described. This motor in the compartment 3 is now operated and will draw the web across to expose the stations on its opposite sides at the opposite windows, and the motor will be actuated intermediate to bring the next station at the window, and then the motor is stopped. At the end of the route the web is simply reversed by actuating the motor connected with the unwound reel.

In Fig. 3 I show the circuit for controlling ten of the devices as described, indicated by 18 and 18' at each of the cars. In each car is a pair of switches 40 and 41 for controlling these motors. It will be seen that each of the motors 18 are connected by a line 43 that passes back by wire 42 through each of the cars, the wire 42 extending through all of the cars is connected with a switch 40 in each car. The line 47 extends through the cars and in each connects with the switch 40 so that closing the switch 40 in any car will connect the line 42 and 47. The line 43 connects with one pole of a source of current at 44, the other pole of which connects with the line 47, therefore, closing any switch 40 will cause the current to flow through all of the motors 18. The other motors 18' in each of the cars are all connected by a line 48 that is joined to the line 46 running back through all cars. The line 45 from the negative terminal of the current source connects with each of the switches 41 that also connect with the line 46. The line 48 also connects with the positive pole at 44, so that closing the switches 41 in any of the cars will send the current through all of the motors 18' in the ten cars. This will actuate the web in one direction in each car. The operator will simply close the switch and inspect the indicator in the car as the web advances, and as soon as the next station, or the one desired appears at the window, the switch is opened. This means that in all of the cars the same advance of the web takes place and they

will synchronize, which will bring the same station to exposed position in each car. For operating the web in the opposite direction in each of the ten cars the duplicate arrangement of switches 41, that will operate motors 18' in the same manner, and advance the web in the opposite direction in each of the ten cars.

It will be seen that to insert the reel, either full or empty, the cap 25 is removed, and then the bottom holder 22 is turned and withdrawn with the empty reel 17 that may be therein, and the full reel inserted in one compartment and the empty reel in the other compartment, the holder on one or both sides is drawn upwardly and the end of the web that is passed between guide rollers 13 from the reel as drawn through the middle casing, and its end attached to the reel in the other compartment, and the slide replaced. In operation the guard in any car simply closes the switch that may consist only of a push button and the empty reel will rotate by its motor and draw the web through the casing at the windows. The guard simply holds the switch closed until the proper station appears and then he releases. And since the motors synchronize the same effect will take place in all cars, as when the reel is placed in the device the same station appears in each car. The operator can of course cause the web to travel for a distance of any number of stations, where certain stations are omitted.

What I claim is:

1. In a car indicator, the combination of a web having the stations printed on both of its sides, a pair of reels for the web, a casing having at each end a compartment containing one reel and a motor, the casing between the compartments being of shallow elongated form with a window on each of the opposite sides arranged to each expose one of the opposite printed sides of the web as drawn from one reel to the other alternately in the opposite directions by one of the said motors.

2. In a car indicator, the combination with a casing having a compartment at each end for a reel and a web connected between the reels through the casing, of a motor in each compartment, the reel being detachably mounted in each compartment and arranged to connect with its motor when inserted, a removable end member for each compartment having a step bearing for the reel.

3. In a car indicator, the combination with a casing having a compartment at each end for a reel and a web connected between the reels through the casing, of a motor in each compartment, the reel being detachably mounted in each compartment and arranged to connect with its motor when inserted, an end member for each compartment having a step bearing for the reel, said casing hav-

ing a window frame on each of the opposite sides arranged to slide upwardly out of the casing to expose the web in the casing.

4. In a car indicator, the combination of
5. a casing having a compartment at each end, a reel in each compartment, a web connected between reels through the casing, a motor in each compartment at the top, the reel being

detachably mounted in each compartment, a clutch arranged to connect the reel with its motor when inserted, and a lower end member for each compartment having a bearing for the reel. ¹⁰

Signed at New York city, N. Y., on 22nd day of January, 1925.

FRANK J. KELLY.
